UNITED STATES PATENT OFFICE.

ALBERT ENGELSON, OF BELLINGHAM, MINNESOTA.

SELF-PROPELLED SLED.

1,272,239.

Specification of Letters Patent.

Patented July 9, 1918.

Application filed March 2, 1917. Serial No. 152,054.

To all whom it may concern:

Be it known that I, ALBERT ENGELSON, a citizen of the United States, and resident of Bellingham, in the county of Lac qui Parle and State of Minnesota, have invented certain new and useful Improvements in Self-Propelled Sleds, of which the following is a specification.

The present invention has reference to sleds; and, the invention relates more particularly to an improved motor driven sled.

The invention has for its principal object to provide a sled having means for propelling the same over snow, ice and the like at a material rate of speed, thus, allowing the same to be successfully used irrespective of the grade of the roads for both pleasure and commercial purposes.

It is also an object of the invention to provide means for maintaining the driving elements of the sled in yieldable engagement with the snow or ice, the said means being capable of adjustment, whereby, the pressure thereof and as a consequence, the pressure on the driving elements, may be varied to accord with the condition of the snow or ice.

Another object of the invention is to provide novel roller means for the sled runners, whereby when the same are engaged with the earth or surface of a roadway, the usual drag caused thereby will be eliminated and hence, the speed of the sled not retarded.

Among other aims and objects of the invention may be recited, the provisions of a sled of the character mentioned with a view to compactness, and in which the number of parts are few, the construction simple, the cost of production small, and efficiency and operation high.

The improvements in the details and arrangements of parts will be apparent from an inspection of the accompanying drawings, in connection with the specific description hereinafter contained, and wherein the preferred embodiment of the invention is disclosed for the purpose of imparting a full understanding of the invention.

In the drawings:

Figure 1 is a top plan of my improved motor driven sled with parts thereof broken away;

Fig. 2 is a longitudinal section in elevation therethrough;

Fig. 3 is a transverse section through the rear runners of the sled; and

Fig. 4 is a fragmental section in detail of a portion of one of the runners.

Referring now more specifically to the several figures of the said drawings wherein like reference characters designate like and corresponding parts; there is provided a frame 1, which frame comprises a plurality of longitudinally arranged bars, certain of the same serving as side bars for the frame, and a plurality of transversely disposed bars, the ends of which are engaged with the longitudinally disposed bars at suitable intervals throughout the length thereof. Cross bars 2 formed of angle metal are engaged with the opposite extremities of the longitudinal bars of the frame 1 and as will be hereinafter apparent, serve not only to brace the said frame structure, but also serve as suitable supporting means.

A plurality of oppositely disposed pairs of runners 3 and 4 are arranged beneath the forward and rear extremities of the frame 1, the forward runners 4 being so mounted as to permit considerable movement thereof whereby the sled will be rendered dirigible. Roller bearings 3' and 4' are rotatably mounted upon the surface engaging portions of the forward and rear runners 3 and 4, and serve as means for permitting the same to pass freely or slide over such exposed portions of earth or roadway as may be encountered by the sled during its travel.

To yieldably support the frame 1 upon the several pairs of runners 3 and 4, elliptical springs 5 are interposed between the same and have their upper portions secured to the adjacent portions of the body 1 as at 6, while the lower portions of the rearwardly disposed elliptical springs are rigidly secured to the upper portions of their respective runners 3 by passing bolts through the same into engagement with the said runners, the bolts being indicated by the numeral 6'. As a means for supporting that portion of the rear end of the frame 1 intermediate the rear elliptical springs 5, a transversely disposed arcuate spring 7 having the opposite extremities thereof offset and seated upon the upper portions of the runners 3 is provided, it being noted that the upper portion of the said arcuate spring bears upon the frame 1, specifically, the intermediate portion, thus, properly supporting the same. To secure the opposite offset extremities of the arcuate springs 7 upon the upper portions of the rear runners

3, the same are preferably passed through bearing openings formed therein and then clamped in position through the medium of the locking bolts 6'. The forward runners 4 have bearing openings formed in the upper portions thereof substantially intermediate the ends of the same and receive therethrough pivot bolts 8, the said pivot bolts being carried by the lower portions of the forward elliptical springs 5 and being locked in engagement with the runners 4 by means of washers or bearing plates 9 which are passed over the remaining extremities thereof and are held in engagement therewith by cotter pins 10 or other suitable fastening devices. An arcuate spring 11 similar to the arcuate spring 7 is arranged transversely of the forward portion of the frame 1 and has its opposite ends offset whereby the same may be passed into engagement with suitable bearing openings formed upon the upper portions of the runners 4 and rigidly secured to the same by means of the pivot bolts 8. By so mounting the forward runners 4, it will be evident, that pivotal movement of the same will be permitted and therefore that the sled may be guided into the desired course.

With a view toward providing means for driving the sled construction over the surface of snow or ice, a plurality of hangers 12 are employed and have certain of the arms thereof engaged with the rear angle metal pieces 2 as at 13 while the remaining arms are forked and snugly engage the adjacent cross bar of the frame as at 14. Elongated bearing openings are formed in the lower portions of the hangers 12 and receive therein driving axles 15, the axles in turn, carrying fixedly mounted spur wheels 16 thereon in spaced apart relation and power transmitting beveled gears 17. Driven shafts 18 universally jointed as at 19 are movably affixed to the frame 1 by means of a plurality of connecting links 20, the said connecting links having their ends looped and engaged with eyelets 21 as arranged upon certain of the cross bars of the said frame while others of the ends thereof are engaged with apertured ears formed upon the opposite sides of a collar portion 22, which collar portion loosely receives therethrough the said driven shaft. Beveled gears 23 and 24 are mounted upon the opposite extremities of the driven shaft 18, it being noted that the beveled gears 23 are in mesh with the power transmitting bevel gear 17 arranged upon the beveled shaft 15, while the remaining bevel gears 24 are engaged with similar gears 25 which are mounted upon a second driven shaft 26 arranged transversely of the frame 1 and having the ends of the same journaled within suitable bearings formed in stub bars 27 arranged between and secured to certain of

the transverse bars of the frame. To support those portions of the universally jointed driven shaft 18 as in proximity of the frame 1, bearing collars 28 are secured to the adjacent cross bar of the frame and loosely receive the same therethrough. Other bearing collars 29 are loosely arranged about the remaining portions of the driven shaft 18, preferably, adjacent the beveled gear 23 and carries thereon laterally extending arms 30, which arms have arranged upon their outer extremities similar bearing collars 31 so arranged as to loosely embrace portions of the driving shaft 15. Thus, by connecting the driven and driving shafts 18 and 15, respectively, the beveled gears as arranged thereon will be constantly maintained in mesh and the proper transmission of driving power insured. Further, upon movement of either of the shafts 15 or 18, they will by reason of their connection be moved collectively.

A plurality of quadrants 32 having suitable offset lower portions are secured to the upper face of the transverse cross bar supporting the bearing collars 28 as at 33 and have pivotally mounted thereon a hand lever 34, the lower portion of the said hand lever being provided with an offset extension 35, the purpose of which will be presently apparent. Arcuate leaf springs 36 are also pivotally connected to the said cross bar as at 37, preferably, adjacent the quadrants 32 and have the free extremities thereof bearing upon the obliquely arranged sections of the driven shaft 18. By so arranging the arcuate springs 36 with relation to the quadrants and diagonally disposed sections of the driven shaft 18, the extension 35 of the lever 34 will be engaged with the same when the said levers are rocked in the proper direction, thus, increasing the tension of the springs and as a consequence, increasing the pressure upon the driven shaft 18 and also upon the spur wheels 16, thereby, forcing the same downwardly into engagement with the surface over which the sled construction is to be driven. By varying the positioning of the lever 34 with relation to the quadrant 32, the tension upon the arcuate springs 36 may be adjusted accordingly and as will be obvious, the spur wheels 16 may be maintained in engagement with the snow or ice under varying pressure.

As a means for driving the spur wheels 16 whereby the sled construction may be propelled, a prime mover, preferably in form of an internal combustion engine 38 is fixedly mounted upon a suitable bed plate 39 as arranged upon the transverse bars of the frame 1 forwardly of the same. A power shaft 40 extends from the crank casing of the engine 39 and is provided with a beveled gear 41 which is in mesh with power transmission means 42 suitably incased and mounted upon the frame and also connected

to the driven shaft 26. A clutch element 43 is interposed between the power shaft 40 and is controlled by means of a hand lever 44 in order that the transmission of power 5 through the said shaft to the transmission means 42 may be controlled by the operator.

A steering column 45, rotatably mounted in brackets indicated by the numeral 46 is extended diagonally downward through the 10 frame 1 to a point whereat the lower extremity thereof is in horizontal alinement with the top portions of the forward runners 4. A connecting link 47 is fixedly mounted upon the lower extremity of the column 15 45 and has pivotal engagement with a plurality of transversely disposed connecting rods 48, the connecting rods in turn extending into engagement with the top portions of the forward runners 4 as at 45. A hand 20 wheel 50 is mounted upon the upper extremity of the steering column 45 and obviously, facilitates the rotation thereof. If desired, control levers whereby the supply of combustive mixture to the internal combustion 25 engine 38 may be regulated at will by the operator or may be passed longitudinally of the steering column into engagement with a suitable quadrant as arranged upon the hand wheel 50. However, since this type of 30 control means is conventional in the art and forms no part of my invention, I desire to have it understood that the same is not limited thereto in any respect but that various modes of control may be substituted or 35 used such as conditions or preference may dictate. A brake drum and band 51 are arranged upon the shaft 26 for an obvious purpose.

From the foregoing, it will be appreciated by workers in the art that I have provided an exceedingly simple motor driven sled, which by reason of its construction 40 may be readily used upon either snow or ice by merely adjusting the positioning of the spur or driving wheels 16 with relation to the surface of the same. Further, should the surface of the snow be soft, thereby, 45 tending to permit the idle operation of the spur wheels 16, the said wheels may be so 50 adjusted as to more positively or surely engage the same by adjusting the hand lever 34 to vary the tension of the arcuate springs 36 upon the driven shaft 18. Such action, as will be understood, will vary the 55 positioning of the spur wheels and should the tension be increased, the spur wheels in turn will be more deeply embedded in the snow. However, when the construction is used in 60 connection with ice covered surfaces, it is evident that but a slight engagement of the spur wheels 16 with the ice is necessary to properly drive the sled thereover. Therefore, but minor adjustment is necessary and

by varying the positioning of the hand lever 34 and hence the tension of the arcuate 65 springs 36 such adjustment will be obtained. Also, by providing the engaging surfaces of the forward and rear runners with the rollers 3' and 4' the sled will be permitted to move freely over such exposed portions 70 of earth or roadway as may be encountered thereby without materially retarding the speed of the same.

It is to be understood that variable speed gearing can be interposed in the power shaft 75 40 in order that the sled may be driven at different speeds.

While I have herein illustrated and described with a considerable degree of particularity, constructional details of the sled 80 embodying my invention, it is to be understood that the invention is not limited to the particular form and arrangement of the several parts which may be modified within a wide range without departing from the 85 essence of the invention, the construction shown and the description based thereon being intended to be taken in an illustrative rather than a limiting sense.

I claim:

1. In a self-propelled sled, a plurality of shafts movably supported adjacent the rear runners thereof, driving means mounted on said shafts, power transmission on the sled, pivotally connected sectional driving shafts 90 intergeared with said transmission and said movable shafts, means for preventing lateral movement of certain of the drive shaft sections, arcuate springs pivotally connected at certain of their ends to the sled and having the remaining ends bearing on certain of the drive shaft sections, and levers mounted adjacent the springs and engageable therewith for varying the tension of the 95 same.

2. In a self-propelled sled, a plurality of hangers having slotted bearing portions formed therein secured to the sled adjacent the rear runners thereof, spurred driving wheels mounted on shafts journaled in said 100 slotted bearings, power transmission on the sled, pivotally connected sectional driving shafts intergeared with said transmission and said movable shafts, means for preventing lateral movement of certain of the drive 105 shaft sections, arcuate springs pivotally connected at certain of their ends to the sled and having at the remaining ends certain of the drive shaft sections, and levers mounted adjacent the springs and having portions 110 bearing upon the same for varying the tension thereof.

In testimony whereof, I affix my signature hereto.

ALBERT ENGELSON.
